LAND MINE

Paul J. M. R. Delalande, Washington, D. C., assignor to United States Ordnance Company, Washington, D. C., a corporation of Virginia

Application July 19, 1940, Serial No. 346,441

13 Claims. (Cl. 102—8)

This invention relates to land mines for military use and more particularly to small mines which may be easily and quickly laid and camouflaged in the expected path of advancing enemy troops or raiding parties. While the invention will be hereinafter described with relation to such a type of mine, it is to be understood that many of the features are applicable to large mines for use against tanks and other vehicles without material modification.

One of the objects of this invention is to provide a simple and practical mine of the above character which will be light in weight and which may be easily and quickly laid and effectively concealed.

Another object is to provide a reliable mine which will be highly effective in use, as well as one which may be inexpensively manufactured and easily transported to the place of installation.

Another object is to provide a land mine which will be safe to handle and may be installed without special tools or unusual skill.

A further object is to provide a land mine which has a wide range of effectiveness and use, and which will be fired from a wide area of approach.

A further object of the invention is to provide a land mine which may be made in a variety of sizes to receive standard ammunition of corresponding size according to the use to which the mine is to be put.

Other objects will be in part obvious from the annexed drawings and in part hereinafter indicated in connection with the following analysis of this invention.

This invention accordingly consists in the features of construction, combination of parts, and in the unique relation of the members and in the relative proportioning and disposition thereof, all as more completely outlined herein.

To enable others skilled in the art fully to comprehend the underlying features of this invention that they may embody the same by the numerous modifications in structure and relation contemplated thereby, a drawing depicting a preferred form of the invention has been annexed as part of this disclosure, and in such drawing like characters of reference denote corresponding parts throughout all of the views, in which—

Fig. 1 is a vertical elevational view largely in section, showing the complete mine in operative or laid position;

Fig. 2 is a similar section of a modified base; and

Fig. 3 is a longitudinal section of a modified firing means.

Referring now to the drawing more in detail, and particularly to Fig. 1, the numeral 1 indicates a container preferably of sheet metal by reason of its strength and water-tightness. This casing is 5 tubular and is provided at its lower end with a strong, substantial base 2, preferably a metallic casting in order to withstand rough handling. The upper part of the casing is closed by a flanged cap 3 of any desired type but preferably one having a snug fit with the tubular casing 1. Interposed between the cover 3 and the casing is a water-tight packing or gasket 4 designed to prevent seepage of water into the mine casing after the casing has been buried in the ground.

15 The cover is secured in any desired manner but preferably by means of a resilient wire catch 5 which extends across the top of the casing, then downwardly and laterally at an angle as indicated to engage diametrically opposite ears or 20 lugs 6 on the casing. This form of connection is desirable as it is adapted weakly to hold the cover in place yet permit easy removal thereof when the mine is expelled. However, it must be sufficiently 25 strong to hold the parts in position under all normal circumstances.

The base 2 is provided with an upwardly extending annular flange adapted to be engaged by a cylindrical sheet metal supporting plate 7, the 30 downwardly extending flange of which coacts with the flange on the base as clearly shown in Fig. 1 to provide a snug fit. Upon this plate 7 is also mounted a boss 8 having an upwardly extending threaded portion which is adapted to contact with the pointed end of a projectile after the fuse has been removed. The boss 8 supports the booster burning powder compound and the detonator as later described.

Connected with the lower central part of the 40 base 2 is a tubular member 9 which extends downwardly and then up one side of the mine casing, as shown clearly in Fig. 1, and is adapted to contain a pyrotechnic compound 10 which may be ordinary black powder, for example. In other words, any suitable compound which will burn 45 easily and rapidly and create a large amount of gas without exploding is satisfactory.

The explosive projectile is indicated at 11 as shown in Fig. 1 and is preferably an ordinary 50 projectile such as used in a 60 mm. or 81 mm. mortar or in a 75 mm. gun. In fact, rejected projectiles which have failed to pass inspection tests for use in cannons or mortars would be suitable. It is merely necessary to unscrew the fuse, that is, 55 the point of the projectile, whereupon the pro-

jectile may be screwed on the threaded boss 8 of the supporting plate.

At the upper end of the flash tube 9 is positioned a trigger mechanism for initiating the operation of the mine. This trigger mechanism as herein shown comprises a tubular casing 12 having a swiveled top or head 13, a draw bolt 14, and a safety latch 15. Within this swiveled head there is positioned a vertically movable firing pin 16 held in retracted position against the action of firing spring 16' by means of the draw bolt 14. Immediately below the firing pin is a detonator 17 mounted in the screw-threaded member 18 adapted to be engaged by the firing pin 16 when the pull bolt 14 has been extracted by means of a wire or lanyard 19.

It will thus be seen that on removal of the draw bolt 14 the firing pin 16 will initiate the ejection of the mine by means of the detonator 17 and combustible compound 10 which generates sufficient gas in the chamber below the supporting plate 7 to eject the projectile against the securing means of the cover 3.

The mechanism above described is of the pull type but obviously the mine may be fired by other mechanisms such as the push type shown in Fig. 3. This trigger mechanism may be screwed into the top of a pipe or flash tube 9 by means of the threaded connection 31 (Fig. 3). The lower end of the tube 32 supports a pedal mechanism 33 having a tubular part 34 telescoping within the casing 32. Within the central part of this tubular member is a compression spring 35 reacting against a firing pin 36 which is held in raised position by means of spring 37 in the lower part of the tubular member 32. A ball 38 coacts with recesses in the firing pin 36, the sleeve 34, and the outer casing 32 in a well known manner. Thus, when the pedal 33 is depressed, the firing pin 36 with the ball 38 is carried downwardly against the resistance of spring 37 until the ball comes opposite an opening 39 whereupon it moves laterally to allow the firing pin to be driven downwardly by the spring 35 against a detonator 40. This detonator ignites the combustible compound 10 in the flash tube 9 as above described and shown in Fig. 1.

The base and flash tube arrangement as described in Fig. 1 is preferable by reason of its simplicity, ease of assembly, and inexpensiveness in manufacture. A modified form, however, is shown in Fig. 2, in which the base member 42 is made in one part with an upwardly extending opening 43 and a side opening 44 on its upper side connected with the bottom of the flash tube 9. The remaining portions of the mine are the same as disclosed in Fig. 1. This arrangement, however, while stronger and better adapted to withstand shocks and handling, nevertheless is heavier and more expensive by reason of the special cores and molds required to cast this base plate.

The preferred manner of using the mine is to bury the same in the ground just below the surface and to cover the same with grass or leaves to prevent notice of the pull wires 9. It is obvious, however, that it is applicable to other uses, particularly in basement windows of buildings, where it is placed horizontally and ejects the bomb laterally on actuation of a pull wire. Also, with the form of trigger mechanism shown in Fig. 3, the device is operable along roads or paths traveled by troops or vehicles. If the mine is made in a larger size, that is, adapted to hold a

five or six inch projectile, for example, it would be particularly suitable for anti-tank defense.

In describing the preferred method of use, it should be borne in mind that the device shown in the accompanying drawing is approximately full-size for a 60 mm. bomb, and the total height or length is not over ten inches. Thus large quantities could be easily carried or transported to the place of use. Usually, a spade-full of earth will permit planting of the mine which is pressed into position by reason of the presser plate 23 which also acts as a recoil plate when the mine is ejected. The dirt is then filled in around and over the mine and the safety latch 15 is unhooked and swung laterally as shown in Fig. 1. One or more pull wires 19 connected at one end of the latch are spread out in various directions likely to be traversed by advancing troops or raiding parties. The end of each wire 19 may be provided with a tethering pin 24, slightly larger than a lead pencil, as it is not always easy to find a tree or bush to which the pull end of the wire 19 can be secured. When in this position the wire, which is almost invisible in the grass or leaves, is very easily engaged by the foot of a passing soldier, and a slight pull upon this wire 19 will extract the draw bolt 14 from the top of the swiveled head 13. The opening supporting this pin is preferably flared at its outer end so that there will be less danger of the bolt sticking or binding after it is removed from engagement with the firing pin 16. It is important to have this head 13 swivel in the crimped end of the tube 9 about the flange at the bottom of the head 13 as at 25 so that it will turn in the direction of pull, for obviously if it were not swiveled and the pull wire extended towards the left from the numeral 14, as shown in Fig. 1, were engaged, then any amount of pull upon this wire would not extract the bolt.

As soon as the firing pin engages the detonator, the combustible charge 10 is ignited and the flash passes into the chamber above the base 2 and forcibly ejects the projectile 11 through the top of the casing, irrespective of its closure. The detonator 20 is preferably of time fuse composition, requiring from one-fifth to one-quarter of a second before it ignites the booster 21 which explodes the main charge normally located in chamber 22 within the projectile. By this time the projectile has been forced upwardly to a height of from two to four feet where it explodes with great force, primarily in a lateral direction, to scatter splinters through an area at least sixty feet in diameter. Thus a series of these mines may be placed across a field at intervals of about one hundred feet and also in rows a hundred feet apart, thereby making the field practically impassable for advancing troops without great danger. The mines have also been discovered to be of great use in the protection of trenches and sentry stations against raiding parties, for it is almost impossible for the raiders to crawl, especially by night, between these mines, if properly placed, without exploding one or more of the mines.

It will thus be seen that the invention is a highly reliable and efficient weapon which may be inexpensively manufactured and assembled. It may be installed by unskilled labor with reasonable safety or, in other words, is substantially foolproof.

Without further analysis, the foregoing will so fully reveal the gist of this invention that others can, by applying current knowledge, readily adapt

it for various applications without omitting certain features that, from the standpoint of the prior art, fairly constitute essential characteristics of the generic or specific aspects of this invention and, therefore, such adaptations should and are intended to be comprehended within the meaning and range of equivalency of the following claims.

I claim:

1. A land mine of the character described comprising a casing with a top closure adapted to be concealed, an explosive shell positioned within said casing, ejector means for said shell at the base of the casing and trigger mechanism for said ejector means, said trigger mechanism including a tube connecting with the base of said casing at one end, a swiveled head on the upper end of said tube, a firing pin in said tube, a detonator to be engaged thereby when said pin is released, and means for releasing said firing pin from a relatively remote distance including a wire adapted to extend in any direction, which, when tensioned, will cause the head to turn towards the direction of pull on the wire and then release the firing pin, thereby to initiate the ejection of the shell.

2. A land mine of the character described comprising a casing, a cover therefor, and a manually operable quick acting means for holding said cover in place in a substantially water-tight condition, said casing being provided with a substantial recessed base, and a supporting plate immediately above said base having a threaded boss and an ordinary projectile having a threaded fuse opening screwed on said boss.

3. A land mine of the character described comprising a casing adapted to hold an explosive projectile, and means for ejecting the projectile from the casing including an external flash tube adjacent said casing and connected therewith a combustible gas-forming mixture which, when ignited, forces out the projectile from the casing, a detonator for igniting said mixture through said tube, and mechanical trigger mechanism for exploding the detonator, said trigger mechanism including a head, and a pull wire leading therefrom.

4. A device as set forth in claim 3, in which the major part of the flash tube between the trigger mechanism and the base of the casing is spaced from but substantially parallel to the casing.

5. A device as set forth in claim 3, in which said flash tube is connected to the upper side of the base of the casing.

6. A land mine of the character described comprising a casing adapted to hold an explosive projectile, and means for ejecting the projectile including a flash tube outside of and parallel to the casing and communicating with the lower part of the casing adapted to contain a combustible gas-forming mixture which, when ignited, will expel the projectile, a detonator therefor in said tube, and trigger mechanism for the detonator, said trigger mechanism including a presser member adapted to be depressed by foot or vehicle, and a firing pin adapted to be released when said member is depressed for igniting the explosive mixture.

7. A land mine of the character described adapted to be buried just beneath the ground level comprising a substantially cylindrical casing having a base adapted to hold an ordinary projectile, a presser plate mounted on the cas-

ing above the base extending laterally therefrom adapted to take up the recoil when the projectile is ejected, an external tube positioned substantially parallel to but outside of the casing and terminating at one end at the base of the casing, and mechanical trigger mechanism at the opposite and upper end of said tube approximately at ground level.

8. A land mine as set forth in claim 7, in which 10 the trigger mechanism includes in said tube a detonator and a firing pin adapted to coat therewith, and a gas-producing mixture within said external tube adapted to be ignited by said detonator for ejecting the projectile.

15 9. A land mine of the character described adapted to be buried just beneath the ground level comprising a substantially cylindrical casing having a base adapted to hold an ordinary projectile, a presser plate mounted on the casing 20 above the base extending laterally therefrom adapted to take up the recoil when the projectile is ejected, an external tube positioned substantially parallel to but outside of the casing and terminating at one end at the base of the casing, and mechanical trigger mechanism 25 at the opposite and upper end of said tube approximately at ground level, the said trigger mechanism including a detonator, a firing pin therefor adapted to be manually released, a cord 30 or the like for actuating said pin and a head on said tube carrying the firing pin and its release mechanism.

10. A land mine of the character described comprising a substantially water-tight generally 35 cylindrical casing having a base and adapted to hold an explosive projectile, means for ejecting the projectile through one end of said casing including an external flash tube adjacent to and substantially parallel to said casing and connected therewith, a combustible gas forming mixture which when ignited generates gas to 40 eject the projectile from the casing, a detonator in said flash tube for igniting said combustible gas forming mixture, and mechanical trigger mechanism for exploding the detonator, said trigger mechanism including a head and a pull wire leading therefrom.

11. A land mine of the character described comprising a substantially cylindrical casing 50 having a base and adapted to hold an explosive projectile, means for ejecting the projectile through one end of said casing including an external flash tube adjacent to and substantially parallel to said casing and connected to the base of said casing, a combustible gas forming mixture which when ignited generates gas to 55 eject the projectile from the casing, a detonator in said flash tube for igniting said combustible gas forming mixture, and mechanical trigger mechanism for exploding the detonator.

12. A land mine of the character described comprising a substantially water-tight casing having a base and adapted to hold an explosive projectile, means for ejecting the projectile from 60 said casing including an external flash tube adjacent to and substantially parallel to said casing and connected therewith, a combustible gas forming mixture which when ignited generates gas to eject the projectile from the casing, a detonator in said flash tube for igniting said combustible gas forming mixture, and mechanical trigger mechanism for exploding the detonator, said trigger mechanism including a presser member adapted to be depressed by foot or vehicle, and a firing pin adapted to be released 65

when said member is depressed for engaging said detonator and igniting the explosive mixture.

13. A land mine of the character described comprising a substantially water-tight generally cylindrical casing having a base and adapted to hold an explosive projectile, means for ejecting the projectile through one end of said casing including an external flash tube adjacent to and substantially parallel to said casing and con-

nected to the upper side of said base, a combustible gas forming mixture which when ignited generates gas to eject the projectile from the casing, a detonator in said flash tube for igniting said combustible gas forming mixture, and mechanical trigger mechanism for exploding the detonator.

PAUL J. M. R. DELALANDE.
